United States Patent Office.

WILLIAM A. LODER, OF ROCHESTER, NEW YORK.

Letters Patent No. 79,843, dated July 14, 1868.

IMPROVED FRUIT-JAR.

The Schedule referred to in these Letters Patent and making part of the same.

TO ALL WHOM IT MAY CONCERN:

Be it known that I, WILLIAM A. LODER, of Rochester, in the county of Monroe, and State of New York, have invented a certain new and useful Improvement in Sealing-Rings for Fruit-Jars; and I do hereby declare that the following is a full and exact description thereof, reference being had to the accompanying drawings, making part of this specification.

Figure 1 is a sectional elevation of my improved jar.

Figure 2, a perspective view of the sealing-ring detached.

Like letters of reference indicate corresponding parts in both figures.

My invention consists of a paper or other flexible ring, whose inside is coated with gum or wax, so that when slipped over the joint, between the jar and cover, the contact or adhesion of the gum will seal the joint.

In the drawings, A indicates an ordinary glass jar, and B the cover, which fits over the top in such a manner as to make a close joint at α , and present a smooth surface of the jar outside.

Over this surface slips a ring, C, made of paper or other flexible material, coated on the inside with gum or wax, which, by contact or adhesion, seals the joint.

I am aware that entire covers made of paper, and coated with gum, covering the top of the jar, have before been used. Such are not only expensive and difficult to make, but the seams are liable to become open, thereby admitting the air. Besides, the contents of the jar coming in contact with the paper, become tainted by the gum; and, furthermore, it has been found nearly impossible to so protect the cover that it will not become wet and soaked, thus rendering the whole worthless, besides destroying the fruit.

In my device the fruit can only come in contact with the glass cover, the paper ring being entirely isolated. The great advantage results, however, from the great cheapness and the facility of manufacture, and the ease of application of the ring. Being made in the form of simple rings, the pieces can be coated with gum, cut in strips, and simply jointed at the ends, when they are ready for application. They are much less difficult to make than one entire cover, which must be made of several parts of different form to apply together.

These rings may be placed in the market as a new and distinct article of manufacture, ready for application to the jars when once finished.

I do not claim a prepared cover coated with gum, as I am aware that the same is not new. Neither do I claim a rubber band or capsule connected with the cover or jar for covering the joint; but

What I claim as my invention, and desire to secure by Letters Patent, as a new article of manufacture, is—

A sealing-ring for fruit-jars formed from a strip or strips of paper, or other flexible material, coated on the inside with gum or wax, for covering the joint between the cover and jar, as herein set forth.

In witness whereof, I have hereunto signed my name in the presence of two subscribing witnesses.
